The ornamental design for a coaxial cable connector nut, as shown and described.

DESCRIPTION

FIG. 1 is a perspective view of a coaxial cable connector nut of the present invention, having a patterned nut.

FIG. 2 is a side elevational view of the coaxial cable connector nut of the present invention, having a patterned nut.

FIG. 3 is a plan view of the coaxial cable connector nut of the present invention, having a patterned nut; and,

FIG. 4 is an opposite plan view of the coaxial cable connector nut of the present invention as shown in FIG. 3, having a patterned nut.

No claim is being made to the features shown in the dashed lines of FIGS. 1-4.
